DESIGN FOR AN ANKLET

Alfred Marum, Lawrence, Mass.

Application December 17, 1940, Serial No. 97,393

Term of patent 3½ years

To all whom it may concern:

Be it known that I, Alfred Marum, a national of the German Reich, residing in the city of Lawrence, county of Essex, and State of Massachusetts, have invented a new, original, and ornamental Design for an Anklet, of which the following is a specification, reference being had to the accompanying drawing, forming a part thereof, in which:

Fig. 1 is a side elevational view of an anklet made in accordance with the present design; and

Fig. 2 is a perspective view thereof in the position in which it appears when worn by an individual.

I claim:

The ornamental design for an anklet, substantially as shown.

ALFRED MARUM.
